UNITED STATES PATENT OFFICE.

TRAUGOTT KERNCHEN, OF RENDSBURG, GERMANY.

CHIMNEY-TOP.

No. 851,942.

Specification of Letters Patent.

Patented April 30, 1907.

Application filed October 12, 1906. Serial No. 338,604.

To all whom it may concern:

Be it known that I, TRAUGOTT KERNCHEN, a subject of the German Emperor, and a resident of No. 3 Altstädtter Markt, Rendsburg, Germany, have invented certain new and useful Improvements in Chimney-Tops, of which the following is a specification.

The present invention relates to a chimney-top which entirely prevents an outer or indirect drafts of air suppressing the escape or withdrawing of the gases and smoke from the stove.

The aforesaid object is attained by the employment of caps which are arranged round the principal eduction-pipe having slits or openings in its side, and the caps are surrounded by a conical shaped case which is covered by a top.

The accompanying drawing represents a form of construction of the invention in perspective view, but with the parts removed from their usual position.

The principal eduction-pipe, the lower end of which is adapted to fix on the chimney over which it is to be employed, is of cylindrical form at its top, and is provided with a flange or foot plate *b* at its bottom. The upper end of the said pipe is provided with several V-shaped slits or openings *c*, and each opening is covered with a cap *d* tapering inward toward the top and rising above the level of the pipe. A case *e* of conical shape is put over the said caps whereby channels are formed between the caps in addition to those under them in such a manner, that the

efficiency of the chimney is considerably increased, and a hinge-like attached head cap *f* which is over the case *e* at a suitable distance from its mouth, prevents rain, the rays of sun etc. going through.

The efficiency of this chimney-top depends on the arrangement of the covered channels, because the air entering by these produces a sucking influence in the mouth of the pipe *a*. The tendency to cause a downdraft in the flue is avoided, and, owing to the said chimney-top not having any movable parts, it is secure from injuries through sudden and violent squalls of wind and the like.

I claim,

In a chimney-top, the combination; an eduction-pipe *a* having a foot-plate at its bottom adapted to fix on the chimney and having V-shaped openings *c* provided at the top end of the said pipe, caps *d* covering each of the said openings and protruding above the level of the pipe, a conical case *e* adapted to be placed over the said caps for holding them together and forming channels between the caps in addition to those which are under the caps through which air can enter in the direction of the head cover *f* whereby the gases of a stove are withdrawn, and the head cover *f* attached to the case *e* by means of a hinge, all as described and shown.

TRAUGOTT KERNCHEN.
